DROP BOTTOM CONTAINER

Frederick K. Fildes, Altoona, Pa., assignor to The Pennsylvania Railroad Company, Philadelphia, Pa., a corporation of Pennsylvania

Application March 11, 1932, Serial No. 598,182

10 Claims. (Cl. 294—71)

My invention, while relating generally to a manner of sealing doors at gravity discharge openings to prevent leakage of material, is more particularly directed to drop-bottom containers such as used for transportation purposes on railway vehicles and motor trucks. The invention is especially adapted to shipping containers wherein grain, cement, sand or other granular material is transported.

10 With a drop-bottom container of the character described, where the bottom doors are made to fit closely within the door frame to prevent leakage of the contents, difficulty is experienced in maintaining the accuracy of fit throughout the life of the container. Inasmuch as the containers are subject to rough usage and handling, the doors soon become distorted, or their hinges become sprung which prevents proper closure of the bottom discharge opening. Thus not long after 15 the containers have been put in service, the doors fail to close properly, and leakage of the contents results.

Accordingly, the principal object of the present invention is to provide a drop-bottom container 20 wherein the bottom doors need not fit with precision within the surrounding door frame, and yet wherein the clearance spaces or crevices between the doors and door frame are effectively sealed against the escape of granular material.

30 Another object of the invention is to provide a drop-bottom container wherein distortion of the bottom doors or springing of their hinges does not destroy the efficiency of the seal which is effected at the discharge opening when the doors are 25 closed.

A further object of the invention is to provide in a container of the character described a resilient sealing strip for bridging the clearance spaces between the doors and door frame, this strip being so disposed with relation to the bottom discharge passage as not to be subjected to excessive wear from the discharge of the container contents.

45 Other objects and advantages characteristic of my invention will become more fully apparent from the detailed description which follows hereinafter, and which has reference to the accompanying drawings, in which there is illustrated 50 one form or embodiment of the invention. Of the drawings:

Fig. I represents a side elevation of a drop bottom shipping container with one-half of the container shown in vertical section.

55 Fig. II represents a plan view of the same, with

one-half of the container shown in horizontal section.

Fig. III represents an end elevation of the same, with certain portions of the end wall and container frame broken away.

Fig. IV represents a cross section of the same, taken at the meeting edges of the bottom doors, as indicated by the lines IV—IV of Fig. II; and

Fig. V represents a cross section of the same, taken at the bottom door hinges, as indicated by the lines V—V of Fig. II.

The container shown in the drawings comprises generally a rectangular body consisting of end walls 1, side walls 2, a pair of hinged bottom doors 3, and a top sheet 4. The top sheet 4 is riveted to 15 a rectangular combing 5 and is provided with a central filling hatch 6 comprising channel beams 7 and a removable hatch cover 8. The hatch cover 8 is fastened to one of the channel beams 7 by a short length of chain 9. Metal battens 20 10 fastened to the top of the hatch cover 8 and dogs 11 hinged to the sides of the hatch 6 are employed to keep the hatch cover 8 tightly closed. The end and side walls 1 and 2 of the container are joined together at the corners by 25 angle bars 12 to which the walls are riveted.

Securely riveted to the center of the upper edge of each end wall 1, there is a roller guide 13 having combined therewith a suspension eye or loop 14. Through the roller guide 13, door operating 30 chains 15 pass, the chains extending downward through housings or channels 16 in the end walls 1. Each door operating chain 15 terminates in a span of chain 17, the two ends of which are secured to the free ends of the hinged bottom 35 doors 3.

At the base of the container the door frame defines a discharge chute or passage and includes slope sheets 18 which are riveted to the end and side walls 1 and 2 and are inclined downward and 40 inward toward the center of the container to a point near the inner flat faces 19 of the bottom doors 3. From this point as clearly shown in Fig. V, each slope sheet is sharply curved, as indicated at 20, and then directed horizontally outward, 45 as indicated at 21, and then vertically downward to form legs or sills 22 for the container to rest upon. Each bottom door 3 is provided with hinges 23 of which the hinge pins 24 are supported by brackets 25 which are riveted through the legs 50 or sills 22 to the side walls 2. The hinge pins 24 are shown secured in place by cotter pins 26.

It will be noted that the bottom doors 3 at their outer edges 27 are spaced at a considerable distance from the side walls 2 and that their flat 55

faces 19 clear the sharply curved portions 20 of the slope sheets 18 by an appreciable distance. This open space is bridged by sealing strips 28 which may be made of rubber impregnated canvas or other material which satisfies certain requirements as to flexibility and resiliency as herein-after explained. The sealing strips 28 are secured to the slope sheets 18 along their curved portions 20 and flat portions 21 by complementary binding strips 29 and by bolts 30. The binding strips 29 cause the sealing strips 28 to be normally directed downward at such an angle, as indicated by the broken lines at 31 in Fig. V, that the projecting ends thereof will substantially 15 clear the path of the discharge when the doors are open.

The sealing strips 28 are of such width that they present a large area at their bottom surfaces adapted to overlap the flat faces 19 of the bottom doors. Thus the pressure of the contents of the container on the top surfaces of the sealing strips 28 presses such strips tightly against the upper faces 19 of the bottom doors, regardless of distortion or other causes affecting alignment of the doors, and serves to maintain an effective seal against leakage all around the door edges. When the bottom doors 3 are allowed to open, the resiliency of the sealing strips causes them to return to the normal angle with the slope sheets 18 and to be withdrawn from the path of the discharging contents, and hence not subjected to severe abrasion which would otherwise take place. Furthermore, the normal position of the sealing strips 28 is such that there is no danger of the margins thereof curling around the outer edges 27 of the doors. If the sealing strips were permitted thus to be bent outwardly, it is obvious that their efficacy would be lost.

At the center of the container near the meeting edges 32 of the bottom doors 3 there is a transverse partition in the form of an inverted V comprising oppositely sloping sheets 33 and a connecting member 34 formed as shown in Fig. IV. The slope sheets 33 and connecting member 45 34 may be welded or otherwise joined together, and they form a triangular partition which divides the door frame into two discharge chutes or passages. In the example illustrated, considerable clearance is provided between the adjacent edges 32 of the bottom doors, and there is also appreciable clearance between their flat faces 19 and the transverse partition. The latter open spaces are bridged by a sealing strip 35 similar to the sealing strips previously described. The sealing strip 35 is held in place by a curved binding strip 36 which is complementary in shape to the connecting member 34 and secured thereto by bolts 37. The normal position of the sealing strip 35 when the doors are open is indicated at 60 38.

Accordingly, the seal effected at the meeting edges 32 of the doors 3 is generally similar to that at the hinged ends of the door. At both regions the sealing strips are adapted to be flexed or bent to overlapping relation with the flat faces 19 of the doors by the closure of the same, and the sealing strips are adapted to spring substantially clear of the discharging contents when the doors open.

70 The operation of the above described container will be apparent from its description and need therefore be only briefly referred to. When the container is filled and ready to be shifted from one place to another, such as from platform or car to platform or car, the bottom door oper-

ating chains 15 are attached to one hook of the hoisting apparatus and the container is lifted by the chains. Additional suspension cables are used to connect the eyes 14 of the roller guides 13 with a second hoisting hook of the hoisting apparatus. After the container has been transferred to the destination at which the contents are to be discharged, the additional suspension cables attached to the eyes 14 are pulled taut and the bottom door operating chains 15 are slackened off by lowering the first hoisting hook above mentioned. This permits the bottom doors 3 to swing downward, and the contents to fall by gravity through the two discharge passages of the door frame, while the suspension cables attached to eyes 14 support the container body in position. The rapidity of discharge may be controlled by the speed and amount of slackening off of the bottom door operating chains 15. In order to close the bottom doors 3 after the contents of the container have been discharged, the described operation may be reversed. The closing of the bottom doors 3 may also be accomplished by holding the bottom door operating chains 15 and slackening off on the additional suspension cables 25 attached to the eyes 14 until the bottom doors 3 are closed and the weight of the container body is again suspended on the bottom door operating chains 15. With the opening of the bottom doors 3, the sealing strips 28 and 35 by reason of their 30 resiliency spring clear of the path of the discharging contents. When the doors 3 are again closed, the sealing strips 28 and 35 are flexed upward into overlapping engagement with the faces 19 of the doors and into overlapping engagement with each other at the corners of the container. They are thus subjected to the pressure of the container contents when the container is filled, preventing escape of material around the door edges.

While I have described one particular example of a container embodying my invention, it will be apparent that various changes may be made in the form thereof without departing from the spirit of my invention as defined in the annexed claims.

Having thus described my invention, I claim:

1. In a container, a door frame defining a discharge chute, a door hinged on said frame, and a sealing strip of resilient material secured to the door frame, said strip extending substantially clear of the path of the discharge when the door is open, but being adapted to be moved by closure of the door to overlapping relation with a portion of the inner face thereof subjected to the pressure of the container contents, whereby the space between said door and door frame is sealed against leakage when the door is closed.

2. In a container, a door frame defining a discharge passage and including a slope sheet at the inside thereof, a door hinged on said frame, and a sealing strip of resilient material secured to the door frame and forming a continuation of said slope sheet, said sealing strip extending substantially clear of the path of the discharge when the door is open, but being adapted to be moved by closure of the door to overlapping relation with the inner face thereof, whereby the space between said door and slope sheet is sealed against leakage when the door is closed.

3. In a container, a door frame defining a discharge passage and including a slope sheet at the inside thereof, a door hinged on said frame, a sealing strip of resilient material forming a continuation of said slope sheet, and a binding

- strip for securing said sealing strip to the door frame and causing said sealing strip to be directed substantially clear of the path of the discharge when the door is open, said sealing strip being adapted to be flexed by closure of the door to overlapping relation with the inner face thereof, whereby the space between said door and slope sheet is sealed against leakage when the door is closed.
5. In a container, a door frame defining a discharge passage and including a slope sheet at the inside thereof, a door hinged on said frame, and a sealing strip of resilient material secured to the door frame and forming a continuation of said slope sheet, said sealing strip normally extending downward from such slope sheet at such an angle therewith as to clear substantially the path of the discharge, but being adapted to be flexed upward by closure of the door to overlapping relation with the inner face thereof, whereby the space between said door and slope sheet is sealed against leakage when the door is closed.
6. In a container, a door frame including side slope sheets, a pair of drop doors hinged at the sides of said frame, a partition extending transversely of said frame at the meeting edges of said doors, said partition comprising oppositely sloping sheets for dividing the door frame into two discharge chutes, and sealing strips of resilient material forming continuations of said side and partition slope sheets, said sealing strips extending substantially clear of the paths of the discharge when the doors are open, but being adapted to be moved by closure of the doors to overlapping relation with the door faces to prevent leakage of the contents when the doors are closed.
7. In a drop bottom shipping container, de-
- signed to discharge from the bottom, drop doors hinged to the end sills of the container at a point materially above the bottom edge of the said walls and out of contact with the under side of the end sills of the container, a housing extending from the top of the container downward to a point below the top plane of the closed doors, and door locking and operating means extending through said housing and connected with said doors.
8. In a drop bottom shipping container designed to discharge from the bottom, drop doors hinged to the end sills of the container walls at a point materially above the bottom edge of said walls, and sills whereby the bottom edge portions of the walls and sill of the container depend below the hinges of the doors and function as drips and deflectors to shed moisture away from the hinges of the door to prevent entrance of moisture into the container, a housing extending from the top of the container downwardly to the bottom of the container below the top plane of the doors in their closed position, and door operating and locking means extending downwardly through said housing and connected to the doors.
9. In a drop bottom shipping container, side and end sills secured to the bottom of the walls of the container, drop doors set up inside the end sills above and out of contact with the under side of the end sills, the lower edge portions of the end sills functioning as drips to prevent moisture entering the container around the door joints, a housing extending from the top of the container downwardly through the container to the bottom thereof below the top plane of the doors, and door operating and locking means extending through said housing and connected to the doors.
10. In a shipping container designed to discharge through its bottom, drop doors secured to the bottom of the container, locking means for holding the doors in closed position and permitting them to open, a housing within the container completely housing said means within the container and open at both ends, the lower open end extending below the top plane of the said doors, whereby moisture in said housing will be discharged through its lower open end outside of the containers.

FREDERICK K. FILDES.
